YARN TENSIONING DEVICE

Archibald T. Guild, Saratoga Spa, N. Y., assignor
to Van Raalte Co., Inc., New York, N. Y.

Application April 6, 1948, Serial No. 19,222

1. Claim. (Cl. 242—153)

1

This invention relates to the textile arts and particularly to a stop motion and means for controlling the tension of yarn or similar filaments.

The present invention will be discussed herein in conjunction with warping machinery, that is, the winding of warp beams preparatory to knitting or other textile fabrication. However, it is to be understood that such use of the invention is by way of example only and the principles disclosed herein may be employed wherever desirable without departing from the spirit or scope of the invention.

In warping it is of the utmost importance that each thread be evenly tensioned, otherwise poor warps and subsequently fabrics of inferior quality result. This is especially true in the warping of fine denier nylon where very light but uniform tensions are essential.

It is also of extreme importance that the warping machine stop automatically whenever a break in a thread or yarn occurs. Stop motions now being used are subject to frequent false stops due to fluctuating tensions. This is a source of considerable lost time for both operator and machine. Present stop motions are also objectionable in not stopping unless stop motion is cleaned very frequently, requiring considerable time.

According to the present invention, means are provided for subjecting yarn passing from one point to another to tension by suspending a weight therefrom, the effect of the weight on the yarn being controlled within close limits by controlling the angular direction of the yarn to and from the weight, despite variations in the amount of slack produced in the yarn by the weight.

In the form of the present invention set forth herein to illustrate the underlying principles one of the weights utilized to tension the yarn serves further as a stop motion element, being adapted to close an electrical machine-stopping circuit by downward movement thereof. Such downward movement of the weight may be occasioned by failure of the strand or by reason of too much slack developing therein to be further taken up by downward movement of the weight.

While it is preferred to run the two devices in conjunction with each other, each device may be used independently of the other. Both tension and stop motion are designed to provide a compensating tension effect on the thread, thereby overcoming the variance in draw from large and small size cones of yarn.

Various mechanical modifications may be

2

made without departing from the present invention, which is not limited to the form shown herein by way of example, or otherwise than as defined in the appended claim.

5. In the drawings:

Fig. 1 is a top plan view of a creel provided with the forms of tensioning and stop motion means disclosed herein by way of example;

Fig. 2 is a cross-sectional view of the creel of Fig. 1, taken on the line II—II of Fig. 1;

Fig. 3 is a side elevational view of one form of tensioning device mounted on the eyelet bar of the creel, the eyelet bar being shown in cross-section;

15 Fig. 4 is a front elevational view of the tensioning device of Fig. 3;

Fig. 5 is a side elevational view of another form of tensioning device mounted on the eyelet bar, the latter again being shown in cross-section;

20 Fig. 6 is a front elevational view of the tensioning device of Fig. 5;

Fig. 7 is a fragmentary cross-sectional view showing a combined tension device and stop motion associated with a guide bar projecting forwardly from the creel, the cross-section being on the line VII—VII of Fig. 1; and

Fig. 8 is an elevational view of the tension device and stop motion of Fig. 7 taken at right angles thereto.

30 In the several figures of the drawing, like characters of reference denote like parts, and the creel proper is designated generally 10 in Figs. 1 and 2. Creel 10 includes a vertical series of longitudinally extending angle irons 12, each of which supports a horizontal row of rotatable spindles 13 which receive cones or cops of thread or yarn 14.

At the front of the creel there is a longitudinal eyelet bar 15 for each horizontal row of cones 14, and the thread from each cone 14 passes through a porcelain eyelet 16 in the eyelet bar 15 and thence through one of the tensioning devices of the present invention which, in this instance, is supported by the lower flange of the angle iron which comprises the eyelet bar proper.

45 Referring to Figs. 3 and 4, each tension device of the form there shown comprises a base 17 which may be of fibre or the like and is fixed to eyelet bar 15 by means of a screw 18 which passes upwardly through the eyelet bar and threads into base 17. A pair of guide elements, designated generally 19 and 20, are disposed upon base 17, and each comprises a pair of upstanding legs joined at their upper ends by an obliquely disposed loop designated 22 in the case of ele-

ment 19 and 23 in the case of element 20. The lower ends of each of the pairs of legs of the elements 19 and 20 are merely pressed into suitable openings provided in base 17. Thread from the eyelet 16 passes through loop 23, thence through a free metal or other ring 25 which extends about all four legs of the elements 19 and 20, thence upwardly through the other loop 22 of element 19.

It will be seen that the thread from loop 23 to the ring and the thread from the ring to loop 22 makes a relatively acute angle which is not greatly varied through the normal range of operation of ring 25. However, increasing tension of the thread at the cone causes ring 25 to rise higher to a point where the thread runs in a much less arcuate angle and the floating tension imparted by the ring 25 is thus materially reduced.

A second form of tension device which may be used in substitution of the device shown in Figs. 3 and 4 is illustrated in Figs. 5 and 6. In this case the tension devices are likewise secured to eyelet bars 15 and include fibre bases 28. The steel wire or like material which makes up the main body portion of the tension device of Figs. 5 and 6 comprises a pair of depending legs 29 and 30 joined at their upper ends by an enlarged loop portion 31. The upper portions of legs 29 and 30 extend obliquely, as shown in Fig. 6, and adjacent the base of loop 31 there is a ring 33 which is soldered, welded, or otherwise fixed at its opposite sides to the upper ends of the legs 29 and 30.

In this form of tension device the yarn or thread from eyelet 16 passes over the lower half of ring 33, as shown clearly in Fig. 6, thence through a freely suspended weight ring 34, thence over the opposite side of ring 33. Here again the lengths of yarn or thread to and from the suspended weight ring 34 makes a relatively acute angle which is not materially varied until ring 34 approaches its upper limit of movement.

Figs. 7 and 8 illustrate a combination tension and stop motion device which is illustrated in Figs. 1 and 2 as being used in conjunction with the tension device of Figs. 3 and 4. Of course, the tension devices of Figs. 5 and 6 may be substituted for the tension devices of Figs. 3 and 4 in this combination and any of the three forms of tension device may be used independently of the others, within the limits of the present invention.

Referring to Fig. 7, yarn from the creel proper comes from the left as viewed in Fig. 7 (from the right as viewed in Fig. 1) and passes over a guide rail 40 which is supported by and extends parallel to a rail 41 which is one of a vertical series of rails projecting forwardly from the left-

hand side of creel 10. Also extending forwardly from creel 10 is a second series of rails or bars 42 which support the tension and stop motion devices of this portion of the present disclosure.

The tension devices proper comprise spaced legs 45 and 46 merging at their upper ends in an enlarged loop portion 47. The lower ends of the legs may be pressed into suitable openings formed in bar 42. The yarn from guide rail 40 passes through a weight ring 48 which extends about legs 45 and 46 and the yarn then passes through an eyelet 50 in rail 41, thence to the beamer.

Besides tensioning the yarn by its dependence therefrom, weight ring 48 serves as a stop motion. A pair of bars 52 and 53 rest in grooves in the upper surface of bar 42; the latter is formed of Bakelite or other insulating material and the bars 52 and 53 are electrical conductors and serve as opposed electrodes of a machine-stopping circuit. When the yarn breaks or too much slack develops, the ring 48 supported thereby falls to the rails 52 and 53, bridges them and establishes a machine-stopping circuit. The details of the electrical circuit form no part of the present invention and any conventional machine-stopping circuit may be employed.

What is claimed is:

In a yarn or strand tensioning device, upright supporting means, means rigid with said support means and comprising a ring disposed adjacent the upper end thereof, and a weight ring disposed about said support means for free vertical movement therealong below said rigid ring, whereby a thread passing over one side of said rigid ring, through the weight ring and over the other side of said rigid ring is tensioned by the weight of the ring suspended thereby.

ARCHIBALD T. GUILD.
